UNITED STATES PATENT OFFICE.

FREDERICK W. HOPPMANN, OF OTTUMWA, IOWA.

DESIGN FOR A PORTABLE CONFESSIONAL.

43,176.

Specification for Design.

Patented Oct. 22, 1912.

Application filed May 29, 1912. Serial No. 700,518. Term of patent 7 years.

To all whom it may concern.

Be it known that I, FREDERICK W. HOPPMANN, a citizen of the United States, residing at Ottumwa, in the county of Wapello and State of Iowa, have invented a new and original and ornamental Design for Portable Confessionals, of which the following is a specification, references being had to the accompanying drawings, forming part thereof.

My design is for a portable confessional.

The figure is a perspective view of a confessional showing my new design.

I claim—

The ornamental design for a portable confessional as shown.

In testimony whereof, I affix my signature in the presence of two witnesses.

FREDERICK W. HOPPMANN.

Witnesses:

ANNA M. ANDERSON,
GEO. PHILLIPS.
